Primary Examiner — Rosemary K Tarcza(74) *Attorney, Agent, or Firm* — JCIP; Joseph G. Chu; Jeremy I. Maynard(57) **CLAIM**

The ornamental design for a wireless charging station, as shown and described.

DESCRIPTION

FIG. 1 is a front view of a wireless charging station; FIG. 2 is a back view of the wireless charging station; FIG. 3 is a left-side view of the wireless charging station; FIG. 4 is a right-side view of the wireless charging station; FIG. 5 is a top view of the wireless charging station; FIG. 6 is a bottom view of the wireless charging station; and, FIG. 7 is a front perspective view of the wireless charging station.

The broken lines in the drawings represent portions of the wireless charging station that form no part of the claimed design.

1 Claim, 7 Drawing Sheets(56)
